DOOR HANDLE AND LOCK

George N. Harden, Marion, Ohio

Application January 7, 1936, Serial No. 57,997

1 Claim. (Cl. 70—303)

This invention has reference to a handle and lock construction and assembly for closures and more particularly for automobile doors.

More particularly the invention has reference to a combination or permutation lock, and an object of the invention is to provide a lock of this character characterized by simplicity of construction and assembly; and which will be found efficient and practical for use on automobile doors.

5 Further objects of the invention are to provide a lock of this character for automobile doors which will dispense with the need of carrying a key for the door lock, and which can be worked from a simple combination easily carried in mind and to that end will enable an operation of the lock under conditions precluding the efficient lighting as is necessary in the case of those locks of a permutation construction and which include a dial for use in setting or releasing the lock.

10 Further objects of the invention are to provide a lock of this character for automobile doors which will dispense with the need of carrying a key for the door lock, and which can be worked from a simple combination easily carried in mind and to that end will enable an operation of the lock under conditions precluding the efficient lighting as is necessary in the case of those locks of a permutation construction and which include a dial for use in setting or releasing the lock.

15 Further objects of the invention are to provide a lock of this character for automobile doors which will dispense with the need of carrying a key for the door lock, and which can be worked from a simple combination easily carried in mind and to that end will enable an operation of the lock under conditions precluding the efficient lighting as is necessary in the case of those locks of a permutation construction and which include a dial for use in setting or releasing the lock.

20 Further in accordance with the present invention a permutation lock of the character mentioned is provided whereby the combination can be worked without relying on "sound" for determining whether or not the combination is being properly worked and which will therefore render it most difficult, if not practically impossible of being picked.

The invention together with its objects and advantages will be best understood from a study 30 of the following description taken in connection with the accompanying drawings wherein:

Figure 1 is an elevational view illustrating an application of the invention.

Figure 2 is an enlarged detail view taken substantially on the line 2—2 of Figure 1.

Figure 3 is a view similar to Figure 2 and showing the parts in position for transmitting movement of the operating handle to the bolt of the lock.

40 Figure 4 is an enlarged detail view taken substantially on the line 4—4 of Figure 2.

Figure 5 is a plan view of one of the disks.

Figure 6 is an edge elevational view of the disk.

Figure 7 is a plan view of a second disk.

45 Figure 8 is an edge elevational view of the second disk.

Figure 9 is a view of one side of a cam disk.

Figure 10 is a similar view of the opposite side of the cam disk.

50 Figure 11 is an edge elevational view of the cam disk.

Figures 12, 13 and 14 are views corresponding to Figures 9, 10 and 11 of a tumbler disk.

55 Figures 15, 16 and 17 are views similar to Figures 12, 13 and 14 of a second tumbler disk.

Figure 18 is an elevational view of a washer.

Figure 19 is an edge elevational view of the washer.

Figure 20 is an elevational view of a shaft.

Figure 21 is an end elevational view of said shaft.

Figure 22 is a perspective view of a dog.

Referring to the drawings it will be seen that the lock and handle of the present invention are illustrated as applied to an automobile door a portion of which is shown in the drawings and indicated generally by the reference numeral 10.

The door 10 is of conventional construction and is equipped with a locking bolt 11 housed within a suitable casing mounted in one side of the frame of the door and operated directly from an inside handle 13 through the medium of a conventional lever 14 mounted on the squared portion of a shaft 15 to rotate with the shaft. Handle 13 as clearly shown in Figures 2 and 3 is suitably secured to one end of the squared portion of the shaft 15 so that by properly manipulating the handle 13 motion is transmitted through the member 14 to the bolt 11 for projecting or retracting the bolt. In this connection it will be noted that at the inside thereof the door 10 is provided with a conventional escutcheon plate 16.

In accordance with the present invention there is provided for the door 10 an outside handle 17 which is suitably connected as at 18 with one end of a squared shaft 19 arranged substantially in alignment with the shaft 15 and provided at its inner end with a cylindrical socket 20 forming a bearing for the cylindrical end 15b of shaft 15. For the outside of the door there is provided a suitable escutcheon plate 21.

Further in accordance with the present invention there is provided on the squared portion of the shaft 15 a disk 22 having a squared opening 23 for receiving said squared portion of the shaft 15 and also provided with a notch 24 in which is pivoted as at 25 one end of a dog 26.

The opposite end of the dog 26 is adapted to engage the periphery of a disk 27 provided with a squared opening 28 receiving the shaft 19. The disk 27 is also provided on its peripheral edge with a flattened portion through which opens a notch 29 which when the disk 27 is in a predetermined position receives the free end of the dog 26 as shown in Figure 3 so that rotative movement of the shaft 19 will be transmitted to the shaft 15 for retracting the bolt 11 in a manner thought to be apparent.

Further the lock includes a pair of tumblers 55

disks 30 and 31 respectively. The disks 30 and 31 are provided at their centers with circular openings 32 and 33 respectively which receive the cylindrical portion 15c of shaft 15 so as to permit rotation of the shaft 15 relative to the disks 30 and 31 under certain conditions.

Each disk 30 and 31 is provided with a circular series of openings 34 and 35 respectively there being preferably twelve openings in each disk corresponding somewhat to the twelve numerals on a clock dial although it will be understood that a greater or lesser number of such openings may be resorted to if desired.

For use with the disk 30 there are provided pins 36 and 37 while for use with the disk 31 there are provided pins 38 and 39.

There is also provided a cam disk 40 which like the tumbler disk is provided with a centrally located circular opening 41 for receiving the portion 15c of shaft 15; said disk being also provided with a circular series of openings 42, the openings 42 being one less in number than the openings 34 and 35 and these openings are adapted to receive pins 43 and 44.

Each disk 30 and 31 is provided at a predetermined point with a notch 45 and 46 respectively while the disk 40 is provided at a predetermined point with a substantially V-shaped notch 47 one wall of which provides a cam surface 48.

The disks 30, 31 and 40 are arranged on the part 15c of the shaft as clearly shown in Figures 2 and 3 and arranged in alternation on said part 15c of the shaft with respect to the disks are spacer washers 49, the washers and disks being so grouped that frictional contact therebetween will serve to prevent too free rotation of the disks, and also to prevent premature transmission of movement from one disk to the other when the lock is being operated.

Projecting from one face of the disk 27 is a properly positioned pin 49a for cooperation with a pin 38 on a disk 31 for a purpose, and in a manner hereinafter made manifest.

Depending from the underside of the dog 26 is a lug 26a which engages in the notches 45, 46 and 47 of the disks 30, 31 and 40 when said notches are aligned as shown in Figure 3 and at which time the free end of the dog 26 is engaged in the notch 29 of the disk 27 so that upon a turning of the handle 17 movement of the handle will be transmitted to the shaft 15 and from the shaft 15 through the member 14 to the bolt 11 for retracting the latter. In this connection it will be understood that when the dog is in the position shown in Figure 2 and the notches of the several disks are out of alignment handle 17 may be freely turned in either direction without effecting a movement of the bolt 11. Thus under such circumstances and with the door of the automobile closed unauthorized entry into the automobile will be effectively precluded.

As is thought to be apparent the holes in the disks, and the arrangement of the pins in the holes will permit a varying of the combination from time to time if desired.

The operation, utility and advantages of the invention will be apparent from the following:

It might be first stated and is thought apparent, that with the pins for each disk arranged in the selected openings in the disks a predetermined manipulation of the handle 17, first turning the same in one direction, and then in a reverse direction for a certain fraction of a revolution, and then for a greater or smaller fraction of a revolution as the case may be, move-

ment of the handle 17 will be transmitted to the several disks in predetermined sequence until all of the disks have been moved into a predetermined position alining the notches in the disks and thereby permitting a movement of the dog 26 from the position shown in Figure 2 to the position shown in Figure 3 whereby to place the handle 17 in driving engagement with the shaft 15, so to speak, so that a further turning of the handle 17 will result in a manipulation of the bolt 11 for retracting the latter.

The manner in which the tumbler disks are successively positioned for alining the notches thereof with one another and with the notch 29 in the disk 27, and the notch 47 in the disk 40 is analogous to the manner in which tumbler disks in any permutation locks are so properly positioned and consequently a detailed description of this particular operation is deemed to be unnecessary. However in actual practice it has been found that by equipping each of the disks 30 and 31 with a series of twelve holes apiece a combination may be formed whereby, in keeping in mind the relative location of the numbers on a clock dial the successive effective positions through which the handle 17 must be moved in working the combination can be readily kept in mind and in addition thereto, one knowing the combination can readily appreciate just when the handle 17 is in each required predetermined position. In this way one having knowledge of the combination may readily operate the lock without the benefit of light while at the same time the combination can be worked without the operator being required to listen for any "click" as is now generally required with permutation locks.

The above may be best understood from the following:

Thus with the pins 36, 37; 38, 39, and 43, 44 arranged in the relative position shown the operator, to retract the bolt 11 will manipulate the handle 17 in the following manner; the handle or knob 17 is first rotated in a clockwise direction until it assumes a position corresponding to, for example, the numeral 11 on the face of a clock dial. This will result in positioning the disk 40 so that its notch 47 is substantially in alignment with the notch 24 in the disk 22. Next the knob 17 is rotated in an anti-clockwise direction to a position corresponding substantially to the position of the numeral 8 on the face of a clock dial. This will result in a movement of the disk 30 to a position alining its notch 45 with the aforementioned notch 48 of disk 40. Next the operator rotates the knob 17 in a clockwise direction and the handle or knob 17 is in a position corresponding to the position of the numeral 6 on the face of a clock dial. This will result in the alining of the notch 46 in the disk 31 with the aforementioned alined notches 47 and 45. The knob 17 is then turned to the left and as the knob is turned in this direction notch 29 in the disk 27 which turns with the knob moves into alignment with the now alined notches 48, 45 and 46. This permits the free end of the dog 26 to drop into the notch 29 with the lug 26a of the dog dropping into the alined notches 48, 45 and 46, the position of the parts being such as shown in Figure 3. With the parts in this position it will be apparent that rotation of the knob 17 in the proper direction will result in a retraction of the bolt 11 permitting the door to be opened.

With the parts in the position shown in Fig-

ure 3, when it is desired to secure the door 10 in closed position against unauthorized opening the dog 26 is raised out of the notch 29 in a manner and through the instrumentality hereinafter described in detail. With the dog 26 in this raised position knob 17 by gravity will rotate to the position shown in Figure 2 thus moving the notch 29 of the disk to an out of the way position so that the free end of the dog 26 will then rest on the peripheral edge of the disk 27 in a manner to hold the lug 26a thereof raised out of engagement with the notches 45, 46 and 47 of the disks 30, 31 and 40 as will be clear from a study of Figure 2.

15 For this raising the dog 26 there is provided a push button 50 mounted to slide in a cylinder or casing 51 mounted in the door structure and secured in position as at 52 at the inner side of the door. Pin and groove means 53, 54 serve to 20 retain the knob 50 against rotative movement and the knob 50 is normally urged to an upwardly projected position through the medium of a spring 55. The knob 50 has a reduced shank that projects through the bottom of the cylinder or casing 51 and at its lower end there is secured to the shank of the knob an angularly disposed arm 55 in the path of which is arranged the pin 44 of the disk 40 as shown in Figure 4.

Thus with the parts in position as shown in Figures 3 and 4 the dog 26 is raised out of engagement with the notch 29 of disk 27 by pressing downwardly on the button 50. Downward movement of the button against the action of the spring 55 will cause the arm 55 to engage the pin 44 thus rotating the disk 40 in a counterclockwise direction. As disk 40 rotates in this direction the cam edge 48 thereof will engage the lower edge of the lug 50 with the result that dog 26 will be caused to swing vertically upwardly 40 from the position shown in Figure 3 to the position shown in Figure 2 and subsequently engage the peripheral edge of the disk 27 whereby said dog will be retained in the position shown in Figure 2 until the knob 17 is again manipulated in a

manner hereinbefore described in detail for placing the handle or knob 17 in driving engagement with the shaft 15.

It is obvious that with the dog 26 in the raised position shown in Figure 2 a haphazard manipulation of the handle 17 will be ineffective for retracting the bolt 11. Thus under such conditions, and with door 10 closed it will be practically impossible for an unauthorized person to gain entrance to the automobile.

While I have described the lock as being particularly adapted for use on automobile doors it will be understood that the same may be applied to doors of other structures or to any other suitable type of closure.

Having thus described the invention, what is claimed as new is:

In a lock of the character described, a pair of aligned shafts, said shafts being normally rotatable independently of one another, and permutation means interposed between said shafts for placing said shafts into and out of driving engagement one with the other, and including a disk mounted on each shaft for rotation with its respective shaft, a dog pivotally connected with one of said disks, and the other of said disks being provided with a notch for receiving the free end of the dog, said permutation means acting to normally retain the free end of the dog out of engagement with said notch, and said permutation means including cam means for raising the free end of said dog out of engagement with said notch and including a disk rotatable about one of said shafts as an axis and provided with a cam surface and a lug on said dog cooperable with said cam surface, a slidably mounted operating button for said cam disk, supporting means for said button, and interengaging means on said button and the cam disk for rotating the latter in a predetermined direction for effecting a raising of the free end of the dog out of engagement with said notch.

GEORGE N. HARDEN.
